(57) **CLAIM**

The ornamental design for a wireless digital display soldering iron as shown and described.

DESCRIPTION

FIG. 1 is a front, right and top perspective view of a wireless digital display soldering iron, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged top plan view thereof.

FIG. 8 is an enlarged bottom plan view thereof.

FIG. 9 is an enlarged view of detail 9 in FIG. 2; and,
FIG. 10 is an exploded view of the wireless digital display soldering iron of FIG. 1.

The dashed broken lines depict portions of the wireless digital display soldering iron that form no part of the claimed design. The dot-dash broken lines in FIGS. 2 and 9 depict the boundaries of the enlarged views and form no part of the claimed design.
